FLUID ACTUATED INJECTION MEANS

Louis J. Garday, Glenview, Ill., assignor, by mesne assignments, to Louis G. Simmons, Chicago, Ill.

Application October 22, 1947, Serial No. 781,427

16 Claims. (Cl. 103—44)

1
This invention relates to liquid injection systems and controls therefor, more particularly to liquid fuel injectors and their control means for internal combustion engines, and it is an object of the invention to provide improved apparatus of this character.

It is a further object of the invention to provide an improved liquid injector pump or the like wherein the liquid from a source under pressure performs the injection of a positively metered quantity of liquid.

It is a further object of the invention to provide an improved fuel injector for an internal combustion engine wherein fuel from a source under pressure performs the injection of a positively metered quantity of fuel.

It is a further object of the invention to provide a fuel injector of the character indicated embodying a metering chamber and improved means for filling the metering chamber from a high pressure source of fuel.

It is a further object of the invention to provide a fuel injector of the character indicated embodying improved means for regulating the capacity of the fuel metering chamber.

It is a further object of the invention to provide a fuel injector of the character indicated embodying improved fuel injection valve actuation means.

It is a further object of the invention to provide a fuel injector of the character indicated embodying improved means for varying the timing of fuel injection.

For a more complete understanding of the invention, reference should be had to the accompanying drawings in which:

Fig. 1 is a plan view partially broken away and partially in section of a fuel injector embodying the invention;

Fig. 2 is a fragmentary front elevational view partially in section of Fig. 1;

Fig. 3 is a sectional elevational view taken substantially along lines 3—3 of Fig. 1;

Fig. 4 is an enlarged elevational view of a valve member shown in Fig. 1;

Fig. 5 is an enlarged elevational view of a valve stop member shown in Fig. 1;

Fig. 6 is an enlarged elevational view of a timing valve plunger shown in Fig. 1;

Fig. 7 is a schematic view of the invention with the elements thereof in position prior to fuel injection taking place;

Fig. 8 is a schematic view similar to Fig. 7 after fuel injection has begun; and

2

Fig. 9 is a schematic view similar to Figs. 7 and 8 after completion of the fuel injection and prior to return of the operating elements to normal position.

5 Referring more particularly to the drawings, the invention is shown embodied in a fuel injector or pump comprising a body 10 of generally rectangular cross section in both its longitudinal and transverse dimensions and adapted 10 to be attached to an internal combustion engine, for example by means of bolts 20. The fuel injector as shown is of the dual injection type in which fuel is supplied to the injector through a single conduit and two separate pulses of fuel are ejected therefrom with a single movement of an engine-actuated cam. Separate fuel metering means and separate valve means are provided to produce the two pulses of fuel with common fuel injection timing means and common means for regulating the amount of fuel ejected.

Extending longitudinally inwardly from the right end of body 10 are the parallel bores 11, 12 and 13 (Figs. 1 and 3), the bore 12 being substantially central of the body and forming a source of fuel under pressure, the bores 11 and 13 being laterally spaced from bore 12 and containing the fuel ejection mechanisms. Extending longitudinally inwardly from the left end of body 10 and in alignment respectively with bores 11 and 12 are parallel bores 14 and 15, the bore 14 containing the valve mechanism controlling the ejection of one fuel pulse and bore 15 together with bore 12 containing the mechanism for timing the fuel ejections. The injector body includes another bore, not shown, corresponding to bore 14 and in alignment with bore 13 to house a second valve mechanism similar to that in bore 14 thereby to provide separate valve mechanisms for producing two fuel injections simultaneously from a single source. Bore 12 at its right end is closed by a timing valve barrel retainer 16 held to injector body 10 by screws 17, a fuel supply conduit 18 being connected to retainer 16 by means of a flange nut 19 to supply fuel under pressure. The fuel conducted to bore 12 is transmitted through passageways to mechanisms in bores 11 and 12 for effecting fuel ejection and is transmitted through other passageways to mechanisms in bores 14 and 15 for preventing valve actuation except at the instant fuel injection is desired and for replenishing the fuel in the metering chambers, as will be explained. 50 The left end of bore 14, as well as the valve

mechanism bore corresponding to bore 13, is closed by fuel discharge connectors 21 attached to the fuel injector body by screws 22 and provided with passageways connected to conduits 23 by the flange nuts 24 to conduct fuel to injection nozzles 25 (Figs. 7 to 9).

Central bores 12 and 15 are separated by an internal shoulder 26 forming a fixed position within the injector so as to properly space the operating elements therein. Abutting against the right edge of shoulder 26 is a timing valve barrel 27 provided with a central bore extending the full length thereof and in which the timing valve plunger 28 is adapted to move. Abutting the right end of timing valve barrel 27, there is a spacing member 29 and abutting this member through a metal sealing ring 32 is the fuel supply barrel 31. The fuel supply barrel 31 is held in position by the timing valve barrel retainer 16 through a metal sealing gasket 33, thereby holding timing valve barrel 27 in position. The metal sealing rings seal each end of supply barrel 31 not only between the members abutting it, but also between the supply barrel and bore 12, since the supply barrel has a conical surface at its left end and valve barrel retainer 16 has a conical surface abutting sealing gasket 33 which, when element 16 is screwed to injector body 10, forces the sealing members outwardly against bore 12. The various members inside of bore 12 are formed with appropriate diameters and finished surfaces so as to be just easily receivable within the bore.

Fuel is continually supplied under high pressure to the inside of barrel 31 which forms a fuel supply chamber 30 from whence the pressure thereof is transmitted through a series of radial holes 34 against one side of pistons 35 arranged to operate within bores 11 and 13, and fuel to be ejected is supplied to the other side of pistons 35 through conduits or passageways extending from chamber 30 to bore 14. Chamber 30 forms a substantially uniform supply of high pressure fuel for optimum operation at all speeds and loads since the source of fuel may be several feet away from chamber 30 and connected thereto through this length of conduit 18.

Bores 11 and 14 are separated from each other substantially centrally of body 10 by an internal shoulder or wall 36. Immediately abutting the right surface of wall 36 is a piston stop plate 37, and abutting stop plate 37 there is a metering piston barrel 38 having a longitudinal bore therethrough in which piston 35 is adapted to move. Spaced longitudinally of metering piston barrel 38 by a metal sealing gasket 39 is the piston stroke control shaft guide 41, and abutting the piston stroke control shaft guide through a metal sealing gasket 40 is a pinion shaft guide 42 provided with a central bore through which the pinion shaft 43 is adapted to pass. Pinion shaft guide 42 includes a circular shoulder against which the inner end of retainer sleeve 44 abuts, the retainer sleeve being held to body 10 by screws 45, thereby holding piston stop plate 37, metering piston barrel 38, piston stroke control shaft guide 41, and pinion shaft guide 42 in proper relationship within bore 11.

Metering piston 35 includes one portion having a diameter closely corresponding to that of the bore in metering piston barrel 38 so as to be movable therein and includes a reduced portion 46 at its left end to provide a space for receiving a coil spring 47 bearing against the larger portion of piston 35 for urging the piston toward its right-

hand position. Piston portion 46, the inside diameter of metering piston barrel 38, the left end of piston 35 and the piston stop plate 37 form a discharge chamber 50 adapted to be filled with fuel oil, a portion of which is ejected therefrom when piston 35 is moved toward the left to abut against piston stop plate 37, diagonally converging holes being provided in piston portion 46, as shown, to permit easier flow of fuel out of the discharge chamber. Piston 35, biased by spring 47, abuts the piston stroke control stop 48 which includes an externally threaded sleeve member received in corresponding threads in piston stroke control shaft guide 41. By rotating piston stroke control stop 48, this being accomplished by rotating the pinion shaft 43 connected to piston stop 48 by a splined coupling 49, the position of piston 35 is determined.

Adjacent the right end of piston 35, the bore in metering piston barrel 38 is enlarged, thereby providing in cooperation with piston stroke control shaft guide 41 and piston stop 48 a piston-actuating chamber 60 into which oil under high pressure is received for moving the piston until it abuts the stop plate. Fuel under pressure is supplied to piston-actuating chamber 60 through the passageway 51 communicating with the source of fuel through openings 34 and the circumferential groove on piston stroke control shaft guide 41, the circumferential groove communicating in turn with the piston actuating chamber by means of diagonal passageways 52. Accordingly, there is a continuous passageway from the rear surface of piston 35 to the inside of chamber 30 so that whenever the fuel injector is in operation there will be fuel pressure exerted against the base of piston 35 thereby urging it toward the fuel ejection position, actual movement except at the proper time being prevented by valves to be described. The high pressure of fuel in the piston-actuating chamber is confined by means of the metal sealing gaskets 39 and 40 which are forced radially outwardly by means of the angular surfaces on guide members 41 and 42 abutting them.

The rotation of pinion shaft 43 to produce variations in the position of piston stop 48 is accomplished through the pinion gear 53 and the toothed rack 54 (Fig. 3), the toothed rack being slidably arranged in a transverse bore within body 10. Gear 53 is relatively loosely received over a pinion hub 55 and is tightly held thereto by a pinion retainer 56 (Fig. 1) which is held to the pinion hub 55 by means of a series of screws 57. Pinion hub 55 is fixed rotatively as well as axially relative to pinion shaft 43 by means of a Woodruff key 58 and the transverse pin 70. The right end of pinion shaft 43 is provided with a spherical bearing surface which abuts against a steel ball 59, the steel ball being received within a spherical bearing surface in the thrust-adjusting screw 61 threaded into a retainer sleeve block 62, in turn threaded into retainer sleeve 44. The screw 61 may be turned to any position thereby determining the position of pinion shaft 43 and may be held fixed in this position by means of the jam nut 63. When the fuel injector is in use, the high pressure in piston-actuating chamber 60 is also exerted against the left end of pinion shaft 43, forcing the pinion shaft tightly against ball bearing 59. Hence if it becomes necessary during the operation to rotate shaft 43 for adjusting the initial position of piston 35, this may be done by moving rack 54 in the proper direction without having the end of pinion shaft 43 exert a high resisting frictional force, the ball

bearing 59 providing a relatively friction-free contact.

Referring to Fig. 3, it will be seen that in bore 13, corresponding to bore 11, there is a retainer sleeve 64 and a centrally extending pinion shaft 65 to which is keyed a pinion hub 66 supporting a ring gear 67 engaging another portion of toothed rack 54 for producing adjustment of a second fuel discharge chamber in synchronism with fuel discharge chamber 60. Pinion hub 66 is keyed to shaft 65 similarly to pinion hub 55 and shaft 43.

The valve mechanism controlling the ejection of fuel from the discharge chamber includes a pair of valves 71 and 76 arranged in series within bore 14 to the left of shoulder 36, the two valves being slidably respectively within central bores of the valve guides 69 and 75. Valve guide 69 abuts the reloading valve seat 68 which abuts the left side of internal shoulder or wall 36, valve seat 68 having a central passageway therethrough as well as a series of angularly extending passageways laterally spaced from the central passageway, the angularly extending passageways communicating with circular grooves on each side of the valve seat. Valve guide 69 includes a longitudinal passageway 72 communicating with a circular groove at the right end of the valve guide which registers with a corresponding circumferential groove in valve seat 68. At the other end of passageway 72 valve guide 69 is provided with a circular cut-out portion forming a chamber 73 into which one end of valve body 71 projects. Spaced between valve guides 69 and 75 is a valve seat 74 having a central opening for communicating with chamber 73 and adapted to be covered by the left end of valve body 71, the central opening connecting with a circular groove at the left end of valve seat 74 through a series of angularly extending passageways. Valve guide 75, similar to valve guide 69, includes a longitudinal passageway 71 communicating at one end thereof with a circular groove registering with a corresponding circular groove in valve seat 74 and communicating with a circular cut-out portion forming a chamber 78 at the other end thereof. Abutting the left end of valve guide 75 is a valve seat 79 including a central passageway for communicating with chamber 78 and adapted to be closed by the left end of valve 76, the passageway also communicating with the passageway in fuel discharge connector 21. The fuel discharge connector abuts valve seat 79 through a metal sealing gasket 81, thereby holding the various members within bore 14 and forming a fluid-tight connection from the inside thereof to the exterior.

The valves 71 and 76 are identical with each other and, as shown in Fig. 4, each includes a relatively long cylindrical portion 82 for guiding these members in the valve guides. At the right end of the valves there is a head portion 83 and at the left end there is a sealing surface 84, the surface 84 being very accurately machined and finished. The surfaces of valve seats 74 and 79 are also very accurately machined and finished so that when the surfaces 84 are against the valve seats an accurate fit is obtained and fuel cannot pass therebetween into the passageways. In order to produce the desired functioning of the valves, the area of surface 84 is considerably smaller than the cross-sectional area of portion 82 and thus smaller than the head 83 thereof.

Valves 71 and 76, when positioned within the corresponding bores of valve guides 69 and 75, have their left ends (surfaces 84) disposed within chambers 73 and 78, respectively, and have their

heads 83 disposed within enlarged portions of the bores forming chambers 92 and 94. Within chamber 92 between the valve seat 68 and the head of valve 71 is a valve stop 85, the valve stop being of such a length that when valve 71 abuts valve seat 74 there is a gap between the end of stop 85 and the head of valve 71. Accordingly, valve 71 may move an amount sufficient to bring its head against stop 85, and to urge valve 71 toward its closed position a spring 86 is arranged between the head of valve 71 and the head of valve stop 85. Similarly, within the chamber 94 there is a valve stop 87 having a length such that valve 76 may move from a closed to an open position, a spring 88 being arranged, as shown, to bias valve 76 to its closed position.

Referring to Fig. 5, the valve stop 85 is shown as including a central bore or passageway 89 communicating with the exterior of the valve stop through radially extending bores 91. The valve stop 87 is similar to stop 85 except that it is not provided with passageways 89 and 91.

Chamber 92 communicates by means of a radial bore in valve guide 69 and a circumferential groove, as shown, with a passageway 93 in body 10, and chamber 94 communicates through a radial bore in body 75 and a circumferential groove thereon, as shown, with a passageway 95 in body 10. Fuel pressure is supplied through passageways 93 and 95 respectively to chambers 92 and 94, thereby urging valve bodies 71 and 76 to their closed positions. The passageway 93 also communicates with the discharge chamber 50 through the passageways 91 and 89 in valve stop 85, the central passageway through valve seat 68 and the bores in the internal shoulder 36 and piston stop plate 37. This passageway fills the discharge chamber with fuel and to close the passageway during the ejecting operation a disc 40 reloading valve 96 is arranged to abut the right side of valve seat 68, the reloading valve being urged toward passageway closed position by means of the coil spring 97. Reloading valve 96 is somewhat smaller than the bore through shoulder 36, whereby the fluid passageway out of the discharge chamber is unimpaired. Passageway 72 in valve guide 69 being in communication with the chamber 73 and with the discharge chamber 50 through the angularly extending bores in valve seat 68 and the bore through shoulder 36, whenever there is fuel in the discharge chamber and the various passageways are filled with fuel, the fuel pressure in chamber 73 urges the valve 71 toward an open position. This urging is resisted by the fluid pressure within chamber 92 acting against the head of the valve communicated thereto through passageway 93.

The passageway from discharge chamber 50 to the conduit 23 leading to the injection nozzle may be closed at one point by the valve 71 abutting its surface 84 against valve seat 74. When valve 71 is open, passageway 77 in valve guide 75 communicates with passageway 72 through the angularly extending bores in valve seat 74 and chamber 73 in valve guide 69, and hence communicates with discharge chamber 50. Since passageway 77 communicates with chamber 78 and thence with conduit 23 through the bore in valve seat 79, there is a complete passageway from conduit 23 to discharge chamber 50 when valves 71 and 76 are in their open position. When valve 76 is in its closed position, i. e., its left end abuts valve seat 79, the passageway from the discharge chamber 50 to the conduit 23 is closed at another point,

thereby closing this passageway at two points to effectively prevent the leakage of fuel there-through. The fuel pressure in chamber 78 urges valve 76 toward its open position, this being resisted by the fuel pressure within chamber 94 communicated thereto through passageway 95. When valve 71 opens, the pressure of the fuel in discharge chamber is exerted against the left end of valve 76, thereby urging it to the open position.

Fuel in the discharge chamber is under pressure at all times by virtue of the fuel pressure behind piston 35, and this fuel pressure is continually exerted against the left end of valve body 71. Piston 35 includes a series of circumferential grooves as shown, one or more of which communicates with radial holes in barrel 38 and thence with conduit 80 whereby fuel leakage into the remaining mechanism from chamber 60 is prevented. Whenever the pressure is released in chambers 92 and 94, the pressure being exerted by the piston in the discharge chamber acting against the valve bodies 71 and 76 in chambers 73 and 78 immediately forces the valve bodies to their open positions to permit the ejection of fuel through a continuous passageway from the discharge chamber to nozzles 25.

The movement of valves 71 and 76 to their open positions, except during ejection, is prevented by fuel pressure alone, and the opening movement is effected by fuel pressure alone when the preventing fuel pressure is released by timing apparatus. The manner of obtaining these pressures may now be described.

Timing valve barrel 27, in addition to its central bore in which timing valve 28 is arranged to move, includes an angularly extending passageway 98 communicating with a circular groove at the right end of timing valve barrel 27 thereby communicating with the inside of fuel supply chamber 30 through the longitudinally extending bores in spacing member 29. The other end of passageway 98 communicates with an internal circumferential groove spaced a relatively short distance from the radial bores 99. Radial bores 99 communicate with a circumferential groove on the outside of timing valve barrel 27, which is of sufficient extent to be in communication with both passageways 93 and 95. The timing valve plunger 28 includes an external circumferential channel 101 of sufficient extent to connect both the radial bores 99 and the passageway 98 through the internal circumferential groove at its left end. Accordingly, when valve plunger 28 is in the position shown in Fig. 1, there is a continuous passageway from fuel supply chamber 30 to the chambers 92 and 94 through the passageways in spacer 29, the passageway 98, groove 101, the radial bores 99, and the passageways 93 and 95 respectively. Consequently, the high fuel pressure from the source through conduit 18 is exerted against the heads 83 of valves 71 and 76 in chambers 92 and 94. The high pressure of the fuel in discharge chamber 50 is also being exerted in chamber 73 against the left end of valve 71, but when valve 71 is closed, that is, its surface 74 is against the corresponding surface of valve seat 74, the high pressure fuel cannot get behind surface 84. Accordingly, the pressure exerted by the high pressure fuel from the discharge chamber tending to open the valve is exerted only against the difference in the areas of surface 84 and the cross section of the valve body 82 (Fig. 4). Since the fuel pressure in chamber 92 is being exerted against an area on the head of the 75

valve equal to cross-sectional area of portion 82, it is apparent that the fuel pressure will maintain valve 71 closed. Similarly, fuel pressure from chamber 30 is exerted through conduit 95 against the head of valve 76 on an area corresponding to the cross section of its body. The pressure in passageway 71 is exerted against the left end of valve 76 upon an area also equal to the difference between the area 84 and the cross-sectional area of portion 82, since fuel under high pressure cannot get behind surface 84 when valve 76 is closed and the greater pressure is exerted against the head of valve 76 thereby maintaining this valve closed against the pressure in passageway 71. Thus, while high fuel pressure is being exerted against the left end of valve 71 and fuel pressure in passageway 71 is exerted against the left end of valve 76, these valves are maintained closed by the fuel pressure in chambers 92 and 94.

Valve plunger 28 includes a central passageway 102 (Fig. 6) and an angular groove 103 cut around the surface thereof, the bottom of the groove communicating through a hole 104 with the bore 102, the bore 102 also communicating with the inside of bore 15 through radial passageways 105. Whenever it is desired to produce a fuel ejection, that is, at the proper time interval, the plunger 28 is moved toward the right until the groove 103 comes into registry with the radial bores 99. When this occurs, there is a completed passageway from chambers 92 and 94 through passageways respectively 93 and 95, radial bores 99, angular groove 103, hole 104, longitudinal bore 102, and radial bores 105 to bore 15, thereby relieving the pressure within chambers 92 and 94. The circumferential channel 101 on plunger 28 is spaced sufficiently away from angular groove 103 so that when plunger 28 is moved toward the right, the connection between passageway 98 and radial bores 99 is closed by the valve plunger, thereby cutting off the pressure of fuel to chambers 92 and 94. Hence when groove 103 comes into registry with radial bores 99, allowing the oil therein to flow out to relieve the pressure in chambers 92 and 94, the pressure within the bore 12 does not affect the operation.

The oil removed from chambers 92 and 94 during the ejection operation passes into bore 15 through the various passageways and is drained from the injector through a passageway 121. In order to prevent any of the oil finding its way into bore 15 from coming out rearwardly thereof, the bore 15 is closed by an oil baffle 122 held within the bore by means of a snap ring 123.

The left end of timing valve barrel 27 projects a considerable distance into bore 15. Surrounding this projecting portion of barrel 27 and abutting against the left side of internal shoulder 26, is a pinion sleeve 106 having a bearing surface on the timing valve barrel so as to be rotatable thereon. The right end of pinion sleeve 106 is provided with gear teeth around its circumference, which gear teeth are engaged with corresponding gear teeth on a timing rack 107 vertically movable in a guide slot in body 10 as shown. Adjacent the left end of pinion sleeve 106 there is a slot or cut-out portion formed therein into which the projecting tongue 108 of timing valve guide 109 is received, the valve guide being rigidly attached to the timing valve plunger 28. Tongue 108 is slidably received in the cooperating groove in pinion sleeve 106 so that when rack 107 is moved vertically to rotate pinion sleeve 106, the timing plunger 28 is also rotated. Since slot 103

is angularly disposed relative to the axis of valve plunger 28, rotation thereof brings a different portion of angular slot 103 into registry with radial bores 99 when the valve plunger is moved toward the right, this effecting a variation in the time at which fuel ejection occurs. The timing valve guide 109 is rotatively and axially fixed to the timing valve plunger by means of a Woodruff key 110 and pin 111 (Fig. 2).

In order to bias timing valve plunger 28 to its outward position, shown in Fig. 1, a valve spring 112 is arranged within bore 15 to abut a valve seat 113, and a timing valve spring collar 114 which is held to the shaft of timing valve plunger 28 through a head on the shaft and a cooperating shoulder on the collar. The valve seat 113 projects inwardly a sufficient distance to hold pinion 106 in its inward position. Surrounding valve spring 112 and collar 114 is a timing valve spring cap 115 of a diameter to be easily received within bore 15, the spring cap 115 including a spherical bearing surface at its left end into which a corresponding spherical bearing surface on a rocker link 116 is received. The other end of rocker link 116 includes a spherical bearing surface received within a cooperating spherical bearing surface at one end of a tappet member 117, the tappet member being pivoted to injector body 10 on a shaft 118. The tappet member is adapted to be rocked backwardly and forwardly through a rocking cam 119 operated from an engine in any manner such as is well understood in the art. The cam 119 has a curved surface 120 bearing directly against one end of tappet member 117 to produce rocking motion thereof. Thus when cam 119 is in the position shown in Fig. 2, timing valve plunger 28 is in its extreme left hand position, and when cam 119 has rotated counterclockwise, the timing valve plunger will be in its right-hand or ejection position.

The upper end of tappet 117 is enclosed by means of a cap 124 held to valve body 10 by appropriate screws.

Arranged to overlie injector body 10 adjacent its right end so as to cooperate with rack 54 to produce adjustment in the capacity of the discharge chambers, is the governor mechanism 125 (Fig. 3) comprising a housing having a transverse bore 126 adapted to be closed at one end by the cover 127 bolted to the housing by bolts 128, and adapted to be closed at the other end by a by-pass valve body 129. A governor piston 131 is reciprocable within bore 126, the governor piston being hollow and receiving a coil spring 132 therein abutting the right end thereof. At the other end of piston 131 there is a cross head 133 provided with a cross pin 134 to which the piston arm 135 is pivoted. Cross head 133 abuts spring 132, whereby the spring normally maintains this member in the position shown in Fig. 3, the cross head being prevented from coming out of piston 131 under the influence of spring 132 by virtue of snap ring 136 received within a cooperating groove in piston 131. Cross head 133 is movable within the piston and to permit this movement piston 131 is provided with a slot or cut-out portion 137 within which the piston arm 135 is adapted to move. On the side of piston 131, opposite to slot 137, gear teeth 138 are arranged as shown and a pinion gear 141 supported in governor housing 125 on a shaft 139 engages gear teeth 138 and the toothed rack 54. Accordingly, when piston 131 is moved in one direction or the other, the pinion 141 is rotated to effect movement of gear rack 54 and hence movement of

pinions 53 and 67 thereby producing variations in the initial position of the ejection pistons 35.

The initial setting of piston 131, and thereby the desired discharge chamber's capacity, is accomplished by moving the indicator 142 to any position along scale 143 indicating the fuel capacity. Indicator 142 is attached to a shaft 144 supported in housing 125, the piston arm 135 being also attached to shaft 144, whereby moving the indicating arm varies the position of piston 131.

Bore 126, needle valve body 129, and the right end of piston 131 form a chamber 145 to which fuel pressure may be supplied from a conduit 146 through passageway 149. In the position shown, fluid pressure exerted against piston 131 would not produce any variation in the position thereof. However, supposing the position of piston 131 is that indicated by broken line 148, fluid pressure exerted against the base of piston 131 would force it to move toward its left-hand position (cross head 133 remaining stationary) and thereby change the position of piston 131 from that determined by the setting of arm 142. Arm 142, once it has been set in a desired position, is held in that position by any desirable means and does not move when fluid pressure is exerted against the base of piston 131. This may occur by virtue of the fact that cross head 133 is movable within piston 131. When there is fluid inside of chamber 145 and piston 131 has been moved toward the left, coil spring 132 is compressed and urges piston 131 toward its right-hand position or that determined by the setting of arm 142. Hence the fuel in chamber 145 is placed under pressure. Fuel may flow out of chamber 145 through a passageway including a valve seat insert 152 to an exit conduit 151. A conical-ended needle valve 153, whose position may be varied relative to valve seat insert 152 by virtue of its threaded engagement within a gland nut 154, cooperates with valve seat insert 152 to permit fuel flow through conduit 151 from chamber 145 at varying rates. Hence when an impulse of fluid pressure has been exerted against the base of piston 131 through conduit 147, the fuel producing this impulse flows out through conduit 151 under the influence of spring 132 urging piston 131 toward its original position, the rate of return being determined by the position of needle valve 153.

The function of the governor mechanism to vary the position of piston 131 after its initial setting by arm 142 is more completely described and claimed in a co-pending application entitled Free Piston Engine, Fuel Control, Serial No. 781,426, filed October 22, 1947, in the name of Louis J. Garday, and which application is assigned to the same assignee as the present invention.

With the foregoing structure and function of individual elements in mind, the coordinated operation of the fuel injector may best be understood and additional structure disclosed by referring to the schematic diagrams of Figs. 7 to 9 in which reference numerals corresponding to those of the other figures are used.

In Fig. 7 the injector and its elements are shown in a quiescent position. That is, rocker link 116 is in its completely outward position whereby spring 112 has urged valve plunger 28 to its extreme outward position interconnecting passageways 98 and 99; conduit 18 being connected to a source of high pressure fuel, chamber 30 is filled with high pressure fuel; high pressure

11

from fuel in chamber 30 is being exerted through conduit 51 against the rear surface of metering piston 35 in chamber 60, the initial position thereof shown having been predetermined by moving rack 54 to the desired position which, through gear 53, has rotated shaft 43 and consequently piston stop 48; high pressure from chamber 30 is exerted against base of piston 35 in discharge chamber 50 through passageway 88, groove 101, passageways 89, 93 and 99; the oil pressure being substantially equal on both sides of piston 35, the piston has moved to its rest position by virtue of spring 47, and discharge chamber 50 is filled completely with oil; reloading valve 96, while biased to close the central passageway through valve seat 68, was lifted off its seat to allow the discharge chamber to fill with oil, and since this has occurred the fluid pressure on each side of valve 96 is substantially the same, whereby spring 38 has caused valve 96 to close the passageway through valve seat 68; the passageway 72 and chamber 73 are filled with high pressure fuel since these passageways are in direct communication with discharge chamber 50; valve body 71 has closed the passageway through valve seat 74 because of the spring 86 and remains closed because high fluid pressure from passageway 93 acts against the head of the valve and the high pressure in chamber 73 is directed against a smaller area; valve 76 has closed the passageway through valve seat 79 because of spring 88 and remains closed because the high fluid pressure from passageway 95 acts against the head of the valve and the pressure in chamber 78 is directed against a smaller area; and assuming that a previous fuel ejection has occurred, the passageway 77, the passageway in member 21 and the conduit 23 are completely filled with oil which will be under a low pressure (that existing after a fuel injection has occurred), this relatively low pressure being exerted against the left end of valve 76 within chamber 78. Hence, the high pressure existing in discharge chamber 50 is kept from the discharge nozzle 25 by both valves 71 and 76. As has already been explained, the area at the head of the valves is substantially greater than that existing at the front ends of the valves so that the difference in force due to fluid pressure acting upon the differential areas is sufficient to maintain the valves closed even against the high fluid pressure from the discharge chamber. Rack 107 has been moved to a position where the angular groove 103 in valve plunger 28 is in the position desired.

The injection nozzle 25 includes a valve plunger 156 held against the valve opening by means of a spring 157.

In Fig. 8 the injector and its elements are shown in their position a short time interval after Fig. 7 and fuel ejection is in progress. That is, rocker link 116 has moved valve plunger 28 to the right thereby bringing angular groove 103 into registration with passageway 99, and also closing off passageway 98 which in Fig. 4 was connected to passageway 99 through groove 101; angular groove 103 has connected the exterior of injector body 10 through passageways 121 and 102 with passageway 99 whereby the oil in chambers 92 and 94 has leaked out and thus relieved the high pressure existing on the heads of valves 71 and 76; since the high pressure in discharge chamber was still exerted through passageway 72 and chamber 73 against the left end of valve 71, this valve has been lifted off its seat against

12

the force of spring 86; this same high pressure being also exerted against valve 96, this valve is tightly forced against its seat and hence prevents leakage of high pressure fuel from discharge chamber 50 through passageway 93; consequently, the high pressure in discharge chamber 50 has been transmitted through passageway 71 and chamber 78 against the left end of valve 76; since the pressure on the head of valve 71 has been relieved, the high pressure exerted against the left end thereof has lifted this valve off its seat also; and there now being a clear passageway from discharge chamber 50 to the injection nozzle 25, the high pressure exerted by the fuel in chamber 60 against piston 35 has forced the fuel to exert pressure through the continuous passageway against valve 156 and has lifted this valve off its seat. Under the influence of fuel pressure from chamber 60, piston 35 has completed a partial stroke to eject a portion of the fuel, the piston continuing to move until it contacts the stop. The stiffness of spring 157 is so chosen that the pressure to lift valve 156 off its seat is greater than the closing pressure of valves 71 and 76. Accordingly, while fuel is being injected, valves 71 and 76 remain open until all the fuel has been injected.

If plunger 28 had been rotated to a different position by the rack 107, the angular slot 103 would have come into communication with passageway 99 a short interval sooner or later, depending on the direction of rotation. With rocker link 116 operating in fixed relationship to the engine, it is apparent that rotating the groove 103 varies the timing of fuel injection.

In Fig. 9 the fuel injector and its elements are shown in their positions following the completed fuel injection with the elements approaching their positions to place the apparatus in a condition for the following ejection. That is, metering piston 35 has moved to its extreme left-hand position with all of the fuel out of the discharge chamber 50; and the valves 71 and 76 have moved to their seated positions under the influence of springs 86 and 88 respectively. This occurs because after fuel injection occurs through nozzle 25 the pressure in conduit 23, as well as in passageways 71 and 72, decreases to a relatively low value, thereby decreasing the fuel pressure urging the valves toward their open positions to such an extent that the springs exert sufficient force to close them. The valve plunger 28 has moved toward its left-hand position due to spring 112 under continued engine operation to a point where the angular slot 103 is no longer in communication with passageway 99 and the channel 101 is on the verge of connecting passageways 99 and 98. At this point, the fuel pressure in passageways 93, 95 and 99 is still low by virtue of the fact that the high pressure was relieved (Fig. 8), and the high pressure from chamber 60 is still being exerted against the rear face of piston 35. Due to the decrease in fuel pressure in nozzle 25, the plunger 156 has taken its seat under the influence of spring 157.

An instant following the conditions shown in Fig. 9, continued operation of the injector moves plunger 28 further to the left from the position shown in Fig. 9 to that shown in Fig. 7, thereby connecting passageways 98 and 99. Hence, the high pressure in chamber 30 is again exerted through passageways 98, 99, 93 and 95 against the heads of valves 71 and 76, thereby forcing these valves tightly against their seats. Under this high pressure, the fuel flows through the

passageways named and flows through passage-way 89 in piston stop 85 lifting the valve 96 off its seat against spring 97 (the fuel pressure opposing movement of valve 96 is low), thereby permitting the fuel to exert high pressure through the passageways named and the discharge chamber 50 against the base of piston 35. Since the same high pressure is now exerted against both sides of metering piston 35, the spring 47 returns the metering piston to its initial position and the discharge chamber fills with high pressure fuel. At the same time, the high pressure is exerted against the left end of valve 71 through passageway 72 and chamber 73, but the high pressure being also exerted against the head of valve 71, this valve remains tightly closed. After the discharge chamber 50 is filled with fuel, high pressure is exerted against both sides of valve 96 and this valve moves to its closed position under the influence of spring 97. Accordingly, the parts are in the position shown in Fig. 7 and are ready for a repeat operation.

The time of fuel injection during operation is small and some lag is produced by the friction and inertia of the parts and the fuel. A complete fuel injection must occur before timing plunger 28 brings channel 101 into registry with passage 99 at which time fuel injection ceases due to the closure of valves 71 and 76. Comparing Figs. 8 and 9, it will be seen that valve plunger moves a distance toward the left equal to the distance between angular groove 103 and channel 101 before fuel injection ceases after initiation thereof. This gives rise to a time interval during which complete injection occurs.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

Having thus described my invention, what I claim and desire to secure by Letters Patent is:

1. A fluid operated fluid injector comprising a body including a passageway therein adapted to be connected to a source of fluid under pressure at one end and forming a discharge opening at its other end, a pair of movable valve bodies for opening and closing said passageway at two points, means for subjecting each of said valve bodies to opposed fluid pressures derived from said source of fluid, differential areas on each of said valve bodies responsive to said opposed fluid pressures to hold each of said valve bodies in a closed position, and means for simultaneously relieving the fluid pressure from one area of each of said valve bodies while exerting fluid pressure on the other area of each of said valve bodies whereby said valve bodies move to open positions.

2. A fluid operated fluid injector comprising a body including a fluid measuring chamber adapted to communicate with a source of fluid under pressure, a passageway in said body communicating with said chamber at one end and forming a discharge orifice at its other end, a piston movable in said chamber under the influence of fluid pressure from said source to eject fluid from said measuring chamber through said passageway, a movable valve body in said passageway adapted to be subjected to opposed fluid pressures derived from said source, differential areas on said valve body responsive to said opposed fluid pressures to hold said valve body

in a closed position, and means for relieving the fluid pressure from one of said areas while substantially maintaining the fluid pressure on the other of said areas, whereby said valve body moves to an open position to effect said fluid ejection.

3. A fuel pressure operated fuel injector comprising a body including a passageway therein adapted to be connected to a source of fuel under pressure at one end and forming a discharge opening at its other end, a pair of movable valve bodies for opening and closing said passageway at two points, means for subjecting each of said valve bodies to opposed fuel pressures derived from said source of fuel, differential areas on each of said valve bodies responsive to said opposed fuel pressures to hold each of said valve bodies in a closed position, and means for relieving the fuel pressure from one area of each of said valve bodies while exerting pressure on the other of said areas, whereby said valve bodies are moved to open positions.

4. A fuel pressure operated fuel injector comprising a body including a fuel measuring chamber adapted to communicate with a source of fuel under pressure for filling said chamber, a passageway in said body communicating with said chamber at one end and forming a discharge opening at its other end, a piston movable in said chamber under the influence of fuel pressure from said fuel source to eject fuel from said measuring chamber through said passageway, a movable valve body in said passageway adapted to be subjected to opposed fuel pressures derived from said source of fuel, differential areas on each of said valve bodies responsive to said opposed fuel pressures to hold each of said valve bodies in a closed position, and means for relieving the fuel pressure from one area of each of said valve bodies while substantially maintaining the fuel pressure on the other of said areas, whereby said valve body moves to an open position to effect said fuel ejection.

5. A fuel pressure operated fuel injector comprising a body including a fuel measuring chamber adapted to communicate with a source of fuel under pressure for filling said chamber, a passageway in said body communicating with said chamber at one end and forming a discharge opening at its other end, a piston movable in said chamber for exerting pressure on one side to eject fuel from said chamber through said passageway, means for communicating fuel pressure from said source to the other side of said piston to effect said fuel ejection, a pair of movable valve bodies for opening and closing said passageway at two points, means for subjecting each of said valve bodies to opposed fuel pressures derived from said source of fuel, differential areas on each of said valve bodies responsive to said opposed fuel pressures to hold each of said valve bodies in a closed position, and means for relieving the fuel pressure on one of the areas of each of said valve bodies while exerting fluid pressure on the other area of each of said valve bodies whereby said valve bodies move to open positions.

6. A fuel pressure operated fuel injector comprising a body including a passageway for conducting fuel derived from a source of fuel under pressure, a pair of valve bodies movable to open and close said passageway at two points, differential areas on each of said valve bodies, the lesser one of the differential areas on each of said valves being adapted to be subjected to the pressure of the fluid in said passageway for urg-

ing said valve bodies toward open positions, means for subjecting the other of the differential areas of each of said valve bodies to an opposing fuel pressure derived from said source of fuel under pressure, said differential areas and the pressures thereon cooperating normally to close said passageway, and means for relieving the pressure from each of said other areas while maintaining the pressure in said passageway, thereby to move said valves to open positions.

7. A fuel pressure operated fuel injector comprising a body including a fuel measuring chamber adapted to communicate with a source of fuel under pressure for filling said chamber, a passageway in said body communicating with said chamber at one end and forming a discharge opening at its other end, a piston movable in said chamber for exerting pressure to eject fuel from said chamber through said passageway, means for transmitting fuel pressure from said source to one side of said piston to effect said fuel ejection, a pair of movable valve bodies for closing said passageway at two points for preventing fuel ejection, differential areas on said valves, means for subjecting the lesser one of the differential areas on each of said valves to the fluid pressure in said passageway to urge said valve bodies to open positions, means for subjecting the other of the differential areas of each of said valve bodies to the pressure of said source of fuel urging said valve bodies to closed positions, whereby said differential areas are responsive to the pressures exerted thereon to normally hold said valve bodies in a closed position, means for relieving the pressure against the other differential surfaces of each of said valves while exerting pressure on the lesser of said differential surfaces thereby to move said valve bodies to open positions.

8. A fuel pressure operated fuel injector comprising a body including a fuel measuring chamber adapted to communicate with a source of fuel under pressure for filling said chamber, a passageway in said body communicating with said chamber at one end and forming a discharge opening at the other end, a piston movable in said chamber, means for varying the initial position of said piston to vary the capacity of said measuring chamber, means for normally transmitting fuel pressure from said source against said piston thereby exerting pressure on the fuel in said chamber and passageway, valve means having differential areas responsive to the fuel pressure in said passageway and the fuel pressure from said source for normally closing said passageway to prevent flow of fuel therethrough, and means for relieving the source fuel pressure from said valve means while maintaining said passageway fuel pressure, thereby effecting valve response to open said passageway and permit the ejection of fuel from said measuring chamber.

9. A fuel pressure operated fuel injector comprising a body including a fuel measuring chamber adapted to communicate with a source of fuel under pressure for filling said chamber, a passageway in said body communicating with said chamber at one end and forming a discharge opening at the other end, a piston movable in said chamber, means for varying the initial position of said piston to vary the initial capacity of said measuring chamber, means for causing said varying means to change the initial position of said piston set thereby, means for normally transmitting fuel pressure from said source against said piston thereby exerting pressure on

the fuel in said chamber and passageway, valve means having opposed differential areas responsive to the fuel pressure in said passageway and the fuel pressure from said source for normally closing said passageway to prevent flow of fuel therethrough, and means for relieving the source fuel pressure from said valve means while maintaining said passageway fuel pressure, thereby effecting valve response to open said passageway and permit the ejection of fuel from said measuring chamber.

10. A fuel pressure operated fuel injector comprising a body including a fuel measuring chamber adapted to communicate with a source of fuel under pressure for filling said chamber, a passageway in said body communicating with said chamber at one end and forming a discharge opening at the other end, a piston movable in said chamber, means for normally transmitting fuel pressure from said source against said piston thereby exerting pressure on the fuel in said chamber and said passageway, valve means having opposed differential areas responsive to the fuel pressure in said passageway and to the fuel pressure from said source for normally closing said passageway to prevent flow of fuel therethrough, and timing means for relieving the source fuel pressure thereby effecting valve response to open said passageway and permit the ejection of fuel from said measuring chamber.

11. A fuel pressure operated fuel injector comprising a body including a fuel measuring chamber adapted to communicate with a source of fuel under pressure for filling said chamber, a passageway in said body communicating with said chamber at one end and forming a discharge opening at the other end, a piston movable in said chamber, means for normally transmitting fuel pressure from said source against said piston thereby exerting pressure on the fuel in said chamber and said passageway, valve means having opposed differential areas responsive to the fuel pressure in said passageway and to the fuel pressure from said source for normally closing said passageway to prevent flow of fuel therethrough, and timing means for relieving the source fuel pressure thereby effecting valve response to open said passageway and permit the ejection of fuel from said measuring chamber.

12. A fuel pressure operated fuel injector comprising a body including a fuel measuring chamber adapted to communicate with a source of fuel under pressure for filling said chamber, a passageway in said body communicating with said chamber at one end and forming a discharge opening at the other end, a piston movable in said chamber, means for varying the initial position of said piston to vary the capacity of said measuring chamber, means for normally transmitting fuel pressure from said source against said piston thereby to exert pressure on the fuel in said chamber and passageway, valve means having opposed differential areas responsive to the fuel pressure in said passageway and to the fuel pressure from said source for normally closing said passageway to prevent flow of fuel therethrough, and timing valve means including timing varying means for relieving the source fuel pressure from said valve means while maintaining said passageway fuel pressure, thereby effecting valve response to open said passageway and

permit the ejection of fuel from said measuring chamber.

13. A fuel pressure operated fuel injector comprising a body including a fuel measuring chamber adapted to communicate with a source of fuel under pressure for filling said chamber, a passageway in said body communicating with said chamber at one end and forming a discharge opening at its other end, a piston movable in said chamber, means for normally transmitting fuel pressure from said source against said piston thereby exerting pressure on the fuel in said chamber and passageway, a pair of valve chambers in said body, a valve body movable in each of said chambers for opening and closing said passageway at two points, spring means in each valve chamber urging said valve bodies to closed positions, said valve chambers opposite said spring end being in communication with said passageway whereby said valve bodies are subjected to the fuel pressures in said passageway urging said valve bodies to open positions, means for subjecting the spring ends of said valve bodies to the pressure of the fuel from said source urging said valve bodies to closed positions, differential areas on each of said valve bodies responsive to said passageway and said fuel source pressures for normally closing said passageway to prevent flow of fuel therethrough, and means for relieving the source fuel pressure while continuing passageway fuel pressure on said valve bodies, thereby to move said valve bodies to open positions.

14. A fuel pressure operated injector for injecting a measured quantity of fuel comprising a body including a fuel measuring chamber, a discharge passageway leading from said chamber and forming a discharge orifice, a piston movable in said chamber for ejecting fuel therefrom through said discharge passageway, means communicating fuel pressure from a source of fuel under pressure to said piston to effect movement thereof, a passageway adapted to connect said chamber and said source of fuel for filling thereof, means for closing said filling passageway, a valve chamber in said body, a valve body movable in said valve chamber for opening and closing said discharge passageway, one end of said valve chamber communicating with said passageway whereby the fuel pressure therein urges said valve body to an open position, a passageway connecting the other end of said valve chamber to said source of fuel whereby said source fuel pressure urges said valve body to a closed position, differential areas on said valve body responsive to said discharge passageway and fuel source pressures to normally close said passageway, and valve means for closing said connecting passageway and thereafter opening a relief passageway to relieve the source fuel pressure from said valve body whereby said valve body moves to a discharge passageway open position under the influence of said discharge passageway pressure.

15. A fuel pressure operated injector for injecting a measured quantity of fuel comprising a body including a fuel measuring chamber, a discharge passageway leading from said chamber and forming a discharge orifice, a piston movable in said chamber for ejecting fuel therefrom through said discharge passageway, means communicating fuel pressure from a source of fuel

under pressure to said piston to effect movement thereof, a passageway adapted to connect said chamber and said source of fuel for filling thereof, means for closing said filling passageway, a valve chamber in said body, a valve body movable in said valve chamber for opening and closing said discharge passageway, one end of said valve chamber communicating with said discharge passageway whereby the fuel pressure therein urges said valve body to an open position, a passageway connecting the other end of said valve chamber to said source of fuel whereby said source fuel pressure urges said valve body to a closed position, differential areas on said valve body responsive to said discharge passageway and fuel source pressures to normally close said discharge passageway, a pressure relief passageway in said body, and valve means for closing off said source of fuel pressure from said other end of said valve chamber and substantially simultaneously therewith connecting said relief passageway to said other end of said valve chamber whereby said valve body moves to a discharge passageway open position under the influence of said discharge passageway pressure.

16. A fuel pressure operated injector for injecting a measured quantity of fuel comprising a body including a fuel measuring chamber, a discharge passageway leading from said chamber and forming a discharge orifice, a piston movable in said measuring chamber for ejecting fuel therefrom through said discharge passageway, means for transmitting fuel pressure from a source of fuel under pressure to said piston to effect movement thereof, a passageway adapted to connect said measuring chamber to said source of fuel for filling said measuring chamber, valve means for closing said filling passageway, a pair of valve chambers in said body, a valve body movable in each of said valve chambers for opening and closing said passageway at two points, one end of each valve chamber communicating with said discharge passageway whereby the fuel pressures therein urge said valve bodies to open positions, a passageway extending from the other end of each of said valve chambers and connected with said source of fuel whereby said source fuel pressure urges said valve bodies to closed positions, differential areas on each of said valve bodies responsive to said discharge passageway pressures and said fuel source pressure to normally close said discharge passageway, a pressure relief passageway in said body, and valve means for disconnecting said source of fuel from said extending passageways and substantially simultaneously connecting said extending passageways to said pressure relief passageway thereby relieving the pressure in said valve chambers at said other valve body ends to effect movement of said valve bodies to open positions.
